UNITED STATES PATENT OFFICE.

JONATHAN S. GREEN, OF PITTSBURGH, PENNSYLVANIA, ASSIGNOR TO THE WESTINGHOUSE AIR SPRING COMPANY, A CORPORATION OF PENNSYLVANIA.

VEHICLE AIR-SPRING.

1,164,182.

Specification of Letters Patent. Patented Dec. 14, 1915.

Application filed April 14, 1913. Serial No. 761,004.

To all whom it may concern:

Be it known that I, JONATHAN S. GREEN, a citizen of the United States, and a resident of Pittsburgh, in the county of Allegheny and State of Pennsylvania, have made a new and useful Invention in Vehicle Air-Springs, of which the following is a specification.

This invention relates to fluid cushion devices and more particularly to air springs for use on motor vehicles, such as automobiles, delivery wagons, trucks, etc.

An object of this invention is to produce a simple, relatively cheap air spring for use in connection with the steel springs of such motor vehicles.

These, as well as other objects which will readily appear to those skilled in this art, I attain in the device illustrated in the single sheet of drawings accompanying this application and forming a part of the same.

In the drawings I have illustrated a vertical section of a device embodying my invention.

The device which I have chosen for the purpose of illustrating this invention comprises an outer cylinder 2 threaded into a head member 3, an inner cylinder 4 telescopically arranged within cylinder 2, and a guard cylinder 5 surrounding cylinder 4 and at times surrounding cylinder 2; that is, during the times when the spring is in compressed condition. Cylinder 4 is provided with a threaded-in bottom 6 and a plunger head 7 threaded into the top of cylinder 4 and which carries a cup leather packing 8 one end of which is secured to a seat 9 on the plunger head by means of a retaining member 10 threaded over the upper end of the plunger head. The upper or free edge 11 of the cup leather packing is forced outwardly so that the cup leather bears against the inner surface of cylinder 2 by means of an expander cone 12 yieldingly pressed against the free edge of the cup leather by a spring 13 located between the upper surface of the expander cone and the lower surface 14 of an enlarged part 15 of the retainer 10. The top 16 of the retainer 10 is flared inwardly and downwardly and at its center is provided with an opening 17. Extending inwardly and upwardly from the central portion of retainer 10 is a flange 18. The flange 18 and the top portion 16 of the retainer

form an oil retaining chamber, and ducts 19 leading from said oil retaining chamber to the cavity containing the cup leather packing keep the upper or free edge of said cup leather packing constantly bathed with oil as will be hereinafter set forth. The plunger head is provided with a downwardly depending tube 20 which forms a pump plunger chamber, and in the lower end of said tube 20 a ball valve 21 is situated. A pump plunger 22 provided with a passage 23 extending therethrough is loosely but positively carried by the head 3 of the cylinder 2 by means of a flanged end 24 which loosely fits within a socket 25 formed therefor within the head portion 3. The pump plunger carries a ball check valve 26 at its lower end. The chamber *a* above the plunger head connects with chamber *b* below the plunger head by means of drilled 75 passages 27 extending through the plunger head and the annular space 28 between plunger 22 and flange 18. A filling opening 29 is provided inside of head 3 and through this opening oil for lubricating and sealing 80 purposes may be introduced to the device to the proper level. An air valve such as used in automobile tires may be carried in the plug for filling opening 29 and the required amount of air for sustaining the load 85 with the air spring in mid position may be forced into the interior of the spring. Guard cylinder 5 is provided with a cap 30 which co-operates with a retaining nut 31 threaded to the outer-lower end of cylinder 90 2 to prevent the longitudinal separation of the cylinders. Cylinder 5 is also provided with a threaded-on bottom member 32 provided with a drain opening 33 for the oil which escapes past the cup leather packing. 95 The drain 33 may be provided if desired with a spring-closed valve which will open outwardly when the pressure within the outer cylinder 5 increases above a certain predetermined amount thereby discharging 100 the oil from the chamber formed by cylinders 4 and 5.

In operation the device will be filled with a medium-bodied lubricating oil to about the point X, and the oil, of course, will fill 105 the entire chamber *b*. As the air spring operates upon its extension and compression movements, oil will be pumped from chamber *b* by means of the pump heretofore described up through passage 23 in plunger 110.

22 and out through the outlet 34 of said plunger into chamber *a* and will fall down through chamber *a* filling the oil retaining chamber *c* formed by flange 18 and the top 6 16 of the retainer. The excess oil pumped will flow back into chamber *b* through annular opening 28. As the leakage of oil past the cup leather will be slight if the cup leather properly fits the interior surface of 10 cylinder 2, the amount which is discharged through drain 33 will be slight and the reservoir formed by chamber *b* will supply the free edge of the cup leather packing with an oil bath for a long period of time. 15 In order to secure the air spring to a vehicle, trunnions 35 are provided on cap 80 and these may be shackled in any desired manner to one end of the steel springs of the vehicle. The cap or head member 8 is provided with securing means 36 in order that 20 the cap 8 may be either rigidly secured to the frame of the vehicle or pivotally connected thereto as desired.

In accordance with the provisions of the 25 patent statutes, I have described the principle of operation of my invention together with the device which I now consider to represent the best embodiment thereof, but I desire to have it understood that the device 30 shown is only illustrative and that the invention can be carried out in other ways.

What I claim is:

1. In a fluid cushioning device comprising relatively movable members having a sliding 35 joint therebetween and forming a closed chamber, a packing for the sliding joint, a chamber above said packing for supplying the same with sealing liquid, a sealing liquid reservoir, and a pump for transferring liquid from said reservoir to said chamber above said packing.

2. A fluid cushioning device comprising relatively movable members having a sliding joint therebetween and inclosing a 45 chamber, a packing for the sliding joint, a liquid receptacle for supplying said packing with sealing liquid, a reservoir for sealing liquid, and a pump for receiving liquid from said reservoir and for discharging it through 50 said chamber to said receptacle.

3. A fluid cushioning device comprising movable members having a sliding joint therebetween and forming a closed chamber, a packing for the joint, a liquid recep-

tacle above said packing for supplying the same with sealing liquid, a reservoir for sealing liquid located within said chamber, and a pump actuated by the relative motion of said members for receiving liquid from said reservoir and for delivering it in a free stream through said chamber to said receptacle.

4. A fluid cushioning device comprising relatively movable members having a sliding joint therebetween and forming a closed chamber, a packing for the sliding joint, a liquid receptacle above said packing for supplying the same with sealing liquid, a reservoir for sealing liquid, a pump mechanically connected to said members and actuated by the relative motion thereof for receiving liquid from the reservoir and for delivering it in a free stream through said chamber to said receptacle.

5. A fluid cushioning device comprising relatively movable members having a sliding joint therebetween and forming a closed chamber, a packing for the sliding joint, a liquid receptacle above said packing for supplying the same with sealing liquid, a reservoir for sealing liquid located within the closed chamber, and a pump located within the chamber and having its parts mechanically connected to said members for receiving liquid from said reservoir and for delivering it in a free stream through the chamber to said receptacle.

6. A fluid cushioning device comprising telescopically arranged relatively movable members having a sliding joint therebetween and forming a closed chamber, a packing for the sliding joint, a pump located within the chamber and actuated by the relative movement of said members for delivering a free stream of sealing liquid through the chamber to the packing, a guard cylinder surrounding one of said members for receiving liquid leaking past said packing and a valve controlling a port formed in said guard cylinder for discharging leakage therefrom.

In testimony whereof, I have hereunto subscribed my name this 10th day of April, 1913.

JNO. S. GREEN
